CLAIM

The ornamental design for a remote control unit, as shown and described.

DESCRIPTION

FIG. 1 is a front view of a remote control unit showing my new design;

FIG. 2 is a left side view thereof, the right side being a mirror image;

FIG. 3 is a back view thereof;

FIG. 4 is a top elevation view thereof; and,

FIG. 5 is a bottom elevation view thereof.

The broken line showing of the buttons in FIGS. 1, 2, 4 & 5 is for illustrative purposes only, and forms no part of the claimed design.
